UNITED STATES PATENT OFFICE.

LOUIS ALBERT LEFRANCOIS, OF SAN FRANCISCO, CALIFORNIA.

POWDER AND PUFF BOX.

1,249,641.

Specification of Letters Patent. Patented Dec. 11, 1917.

Application filed March 8, 1917. Serial No. 153,358.

To all whom it may concern:

Be it known that I, LOUIS ALBERT LEFRANCOIS, a citizen of the United States, and a resident of San Francisco, in the county of San Francisco and State of California, have invented a certain new and useful Improvement in Powder and Puff Boxes, of which the following is a specification.

The present invention relates to toilet articles, and more particularly to a container for powder and a puff.

An object of the present invention is to provide a container having separate compartments, one for the powder, and another compartment for the puff to prevent the puff from being completely enveloped in the powder during the handling of the container, and to accommodate a relatively large amount of powder.

Another object of the present invention is to provide a container body with an adjustable cover part having a mirror thereon, and adapted to swing up to bring the mirror into use, and to provide a body constructed to support the cover part when raised without tilting the container.

The invention further aims at the provision of a container having superposed compartments, and a novel hinge and clasp structure for uniting the parts of the container for individually opening and closing the compartments.

A still further object of the present invention is to provide a container of relatively simple and compact structure, and which is adapted particularly for travelers' use, which comprises relatively few parts, and which may be economically manufactured.

The above and various other objects and advantages of this invention will be in part described, and in part understood, from the following detailed description of the present preferred embodiment, the same being illustrated in the accompanying drawing wherein:

Figure 1 is a transverse section through a powder and puff box constructed according to the present invention.

Fig. 2 is a longitudinal section taken through the same.

Fig. 3 is an end elevation, of the container.

Fig. 4 is a front elevation of the same.

Fig. 5 is an end elevation of the con-

tainer, disclosing one of the compartments open.

Fig. 6 is a horizontal section taken through the upper compartment, showing a powder puff arranged therein.

Referring to this drawing, wherein like parts are designated by similar characters of reference throughout the several views, 10 designates the body or base portion of the container which may be formed of metal, 65 glass, porcelain or any other suitable material.

The bottom 11 of the container is relatively thick and heavy to prevent the tilting of the body portion and the side walls, and 70 end walls, preferably taper upwardly to the upper edge of the body 10. The space within the body 10 is relatively large and is adapted to carry powder or the like.

The body 10 is adapted to be closed at its 75 upper open end by an upper compartment or section 12 which is in the form of a relatively shallow casing made preferably from sheet metal and provided at its lower edge with an outstanding bead 13 terminating in 80 an inwardly offset and downwardly directed flange 14 adapted to fit in the open upper end of the body 10 to center the bead 13 upon the upper edge thereof.

The compartment or casing body 12 is 85 closed at its lower end by a partition disk or plate 15 engaged at its marginal edge in the bead 13, and adapted to support against its under side a mirror 16 which is held against the partition 15 by the flange 14, 90 the latter being seated against the beveled marginal edge of the mirror 16.

The upper compartment or casing 12 is closed by a removable cover 17 in the form of a disk seated upon the upper edge of the 95 casing 15 and being provided with a depending inwardly offset flange 18 adapted to bind in the upper end of the casing 12.

The back wall of the body 10 is provided, adjacent to its upper edge, with a pair of 100 spaced-apart outstanding lugs 19 between which is fitted the lower rolled over end of a hinge strap 20 forming an eye to receive a pivot pin 21, carried by the lugs 19. The strap 20 extends upwardly about the bead 13, and is soldered, or otherwise suitably secured against the back wall of the upper compartment 12. The upper end of the strap 20 is hingedly connected to the cover 17 by means of a strip 22 which is soldered 110

or otherwise secured to the cap 17 and connected to the strap 20 by a pivot pin 23. The upper part or section of the container may thus be swung upwardly upon the body 10 5 to open the latter while the cap or cover 17 is retained in closed position. The cover 17 may also be raised to open the upper compartment without uncovering the contents in the body 10.

10 The upper part of the container is held closed against the lower part by means of a spring tongue 24 secured to the casing 12 and extending downwardly about the bead 13 and provided with an apertured lower 15 end. The body 10 has on its front wall an outwardly extending projection or lug 25 adapted to fit in the aperture of the spring tongue 24 to secure the hinged parts together. The cover 17 is in a like manner 20 held in locked position upon the casing 12 by a second spring tongue 26 which is secured to the cover 17 and provided with an opening near its free end adapted to receive a lug or projection 27 which is pressed or 25 stamped outwardly from the upper end of the spring tongue 24. The tongue 26 is arranged in overlapping relation with respect to the upper end of the spring tongue 24 so that the latter not only provides means for 30 engaging the body 10, but also means for engaging the spring tongue 26 of the cover 17.

In use, a quantity of powder A is placed in the lower compartment in the body 10, and a powder puff or the like B is placed 35 in the upper relatively shallow compartment or casing 12.

When it is desired to use the mirror 16, it is only necessary to engage the thumb or finger beneath the lower end of the spring 40 tongue 24 and disengage the tongue from the projection 25 when the top part of the container may be swung upwardly upon the

pin 21 and held at the desired angle by the stop lug 28. As the bottom 11 is relatively heavy, and as the side and end walls of the 45 body part 10 are relatively thick at their lower ends, the body is given sufficient stability to support the upper part when in raised position without tilting the container.

The upper compartment may be opened 50 by lifting the spring tongue 26 out of engagement with the projection 27 to remove the powder puff B, and the upper compartment may then be swung to one side to open the lower compartment so that access may be 55 gained to the powder A contained therein.

It is readily seen that in traveling, and in handling the container, that the powder is held in a separate compartment and cannot envelop the powder puff B.

60 It is of course understood that various changes and modifications may be made in the details of construction of the above-described powder and puff box without departing from the spirit of this invention, and being restricted only by the scope of the following claim.

I claim:

In a container, the combination of a body part, having an outstanding projection, a 70 hinged part mounted on the body part, a cover hingedly mounted on the hinged part, a spring tongue carried upon the hinged part and having an opening at its lower end for engagement with the projection of the 75 body part to hold the hinged part in closed position thereon and provided near its upper end with an outstanding projection, and a second spring tongue carried by said cover and having an opening therein 80 adapted to engage the projection of said first spring tongue.

LOUIS ALBERT LEFRANCOIS.
